UNITED STATES PATENT OFFICE.

FREDRICK W. SMITH, OF NORTH TONAWANDA, NEW YORK.

ELECTROPNEUMATIC ORGAN.

1,231,212.

Specification of Letters Patent. Patented June 26, 1917.

Application filed September 16, 1911. Serial No. 649,772.

To all whom it may concern:

Be it known that I, FREDRICK W. SMITH, a subject of Great Britain, residing at North Tonawanda, in the county of Niagara and State of New York, have invented a new and useful Electropneumatic Organ, of which the following is a specification.

This invention relates to electro-pneumatically operated musical instruments.

10 The invention has for one of its objects the provision of a tracker-board of novel construction which is provided, in addition to the usual openings, with a master opening and other openings arranged, combined and related to the master opening and to the ordinary note openings in a new manner, these additional holes or openings being adapted for use in connection with certain other improved and novel instrumentalities and with 20 the perforated music sheet for the control of one or more organs, pianos, or other musical instruments.

Another object of the invention is the provision of a tracker-board having, in addition to the usual note holes or openings, a master hole or opening and other holes and an electro-pneumatically operated system of novel arrangement and novel features combined therewith in a new manner and with a 30 multi-manual pipe or reed organ or piano, whereby the different manuals are automatically controlled by the music sheet so that they are rendered adaptable for playing by the music sheet, and to enable any two or 35 more manuals to be automatically played simultaneously and any change in playing from one manual to another may be arranged; further, whereby all changes of registration on the draw stops, couplers, swell 40 shades, combinations or other movements involved in organ playing may be effectuated.

Another object of the invention is the provision of different novel apparatus for the control of electrical switches and the control 45 of electric circuits in an electro-pneumatically operated and controlled system for musical instruments.

The invention embodies, first, a tracker-board having a new arrangement of perforations or holes and a master hole, in addition to the ordinary note holes; second, the combination of such novel tracker-board with a novel electro-pneumatically operated and controlled system for playing musical instruments; third, a novel electro-pneumatic circuit controller; fourth, a novel electro-pneu-

matic switch operator; fifth, a novel pneumatically operated contact; and, further, certain improved constructions and combinations; and systems, all of which will be 60 more fully set forth hereinafter.

In the accompanying drawings:

Figure 1 is a diagrammatic view of the complete invention, certain of the new electro-pneumatic mechanisms being shown in 65 section;

Fig. 2, a detail section of one of the electro-pneumatic apparatuses;

Fig. 3, a detail section of a controlling apparatus;

Fig. 4, a detail section of one of the pneu- 70 mato-electric switches;

Fig. 5, a detail section of a circuit controlling apparatus;

Fig. 6, a detail section of an electrically 75 controlled pneumatic for an organ pipe;

Fig. 7, a face view of a part of the switch- 76 board;

Fig. 8, a similar view showing one of the switch bars;

Fig. 9, a cross-section on line 9—9, Fig. 8;

Fig. 10, a top view of Fig. 8;

Fig. 11, a bottom view thereof, and Fig. 12, a diagrammatic view showing the electrical and pneumatic circuits and devices 85 employed in sounding a note.

T designates a section of a tracker-board which is provided with the usual note holes 1' which control the pneumatics that sound the musical instrument, whether the latter 90 be an organ or piano and whether electro-pneumatically, pneumatically, or mechanically operated. The holes or openings 1' are one hundred and ten in number and all of these holes except those included in the 95 transverse rows T' which appear at 1'' are used as playing holes. In addition to the note holes 1' I provide series of other holes T' which control the action of the musical instrument in such manner as to throw on or 100 off the different organs or manuals to be played electro-pneumatically by means of the perforations in the music sheet which passes over the tracker-board at will. The tracker-board has in all two hundred and 105 forty-three holes, more or less, as may be required, the number of the holes depending on the size of the instrument and the number of the various organs or other musical devices to be operated. Of this total of two 110 hundred and forty-three holes, more or less, the note holes 1' constitute one hundred and

ten to provide for the different manuals and which are divided between solo and accompaniment. Each series of holes T' consists of two rows, one row being adapted to throw the organ or musical instrument actions on and the other row to throw them off in a manner which will appear hereinafter. The openings $1''$, while in line with note openings $1'$, are not note openings but are a part of the control openings T' .

10 I provide a separate hole or perforation Z in the tracker-board which is in the nature of a "master hole" for the reason that in controlling the various electrical switches, it controls the master switch R . I also provide the single row of controlling holes T^2 which includes the hole T^3 forming no part of the series of playing or note holes $1'$.

Leading from the holes $1'$, as indicated by the broken lines K' , are small air tubes or pipes which extend to the pneumato-electric contacts K , one of which is shown in Fig. 4, these contacts corresponding in number to the playing or note holes in the tracker-board with which their pipes K' are connected. The contacts K control the electric circuits, in the first instance, said circuits receiving their energization from the electric battery U , and all of the electrical energizations of operative parts hereinafter described are controlled by the pneumato-electric master switch R which is of the construction shown in Fig. 4, so that except when the master hole or perforation Z is uncovered by the music sheet, regardless of what other holes are uncovered, electrical energization of the parts cannot occur. There are one hundred and ten of the switches K , one for each of the note holes $1'$.

40 Pneumato-electric switches K^4 corresponding in construction to the switches K and in number to the controlling holes T' , including the holes $1''$, are connected by pipes K^3 to said holes. Pneumato-electric switches K^5 corresponding in number to the controlling holes T^2 , T^3 , are connected to said holes by pipes K^2 .

I also provide electro-pneumatic switch 50 operators L whose purpose is to throw on or off the electric switches of the electric switch-board N to thereby pull the stops of the organs 100, 101, 102, 103, these being, respectively, the great organ, the choir organ, the swell organ and the solo organ. There are as many (four in the present instance) of the switch operators L as there are organs. One of these electric switch throwers is shown in detail in Fig. 2 and all 55 may be of the same construction. A modified construction of the electro-pneumatic apparatus L is shown at M in Fig. 6 and is used to operate the valve in the chest admitting air pressure to the organ pipe when 60 it is played.

The electric switch-board N , Figs. 7 to 11, has a plurality of fixed metallic plates N' (sixty-one in the present instance) a portion of which appear. These plates have circuits S^{10} , S^{11} , S^{12} , S^{13} , in the form of cables, each having a plurality of electrical conductors (sixty-one in the present instance), the independent conductors S of which run to the sixty-one organ pipes provided in each of the respective organs 100, 70 101, 102, 103, whereby the pipes P , of which there are sixty-one in each organ, are electro-pneumatically operated. The cables S^{10} , S^{11} , S^{12} , S^{13} , have their respective conductors (sixty-one for each organ) connected to 80 independent sets of switch bars or plates N' . The switch-board plates N' are set vertically and insulated from each other, each of the sixty-one wires of any cable running from its plates to its corresponding apparatus M of which there are sixty-one for each organ; thus there is a wire or circuit from an apparatus M for the "C" pipe to the first of the metallic plates on the switch-board; another from the "C#" pipe to the second 90 of the plates and so on. The switchboard has rockable switch bars $30'$ corresponding in number to the organs, there being four such bars $30'$ in the present instance to control the organs 100, 101, 102, 103. Each 95 switch bar $30'$ carries contacts $31'$ corresponding in number to the plates N' , there being sixty-one contacts $31'$ on each bar in the present instance, to control the circuits of the sixty-one apparatuses M of the given 100 organ and thus to independently control the sixty-one pipes of that organ.

The pneumato-electric contacts K^4 , K^5 , R , are of the construction shown in Fig. 4, the contacts, except the master contact R which 105 is single, being preferably arranged in multiple and contained in a single case or box which is provided in its lower part with a plurality of chambers $4'$, each connected by its own pipe, such as K^4 to its hole in the 110 tracker-board. Above each chamber $4'$ is a suction chamber $2'$. All of the suction chambers $2'$ are connected to any suitable suction reservoir which may be employed to provide suction for the apparatus. The 115 chambers $2'$ and $4'$ are connected by bleed holes $6'$ and each set of chambers is separated by its own diaphragm $7'$. Above the chamber $2'$ is a contact chamber $2''$, an opening connecting said chambers, but the 120 two chambers are sealed against communication by a flexible diaphragm $8'$. There is a stem $9'$ disposed between the diaphragms and having a part extending through diaphragm $8'$ and provided with a button $10'$, 125 by which an electrical spring contact $11'$ may be made to engage another electrical contact $12'$ located in chamber $2''$; the contacts $11'$ and $12'$ are normally separated and the diaphragm $7'$ is depressed. When an 130

opening in the music sheet registers with an opening in the tracker-board, atmospheric pressure passes into the corresponding chamber 4', and overbalances the suction on opposite sides of the diaphragm 7' so that the diaphragm 7' lifts, the stem 9' is forced up and the button 10' forces the contact 11' into engagement with the contact 12', thus completing the given electrical circuit of the circuits Q.

The organ-pipe-controlling circuits S^{10} , S^{11} , S^{12} , S^{13} , are each controlled at the switch-board N by an electro-pneumatic apparatus L, shown in detail in Fig. 2, four of the apparatuses L being used in the present instance. This apparatus has a chamber 13' subject to air pressure from any suitable air pressure source through a pipe 28'. There is a lower chamber 15' in communication with the pressure chamber 13' by a port 14', and located in the chamber 13' is a motor bellows 19' which has no communication with said chamber 13' save through a port 17', the chamber 15' and the port 14'.

A port 16' constitutes an outlet for the chamber 15'. Located within, but out of communication with the chamber 13', is a valve-operating bellows 18' which is connected to a valve stem 21' carrying a valve 22' which is adapted to seat over and to close either the port 14' or the port 16' and to either cut off chamber 13' from chamber 15' or to place said chambers in communication. When said chambers are cut off, the pressure in bellows 19' can exhaust through port 16'. Mounted on the apparatus is a chamber 22'' which is in communication by a port 27' with the interior of the bellows 18' and is also in communication with the atmosphere through a port 25'. Apertures 26' afford communication between the chamber 13' and the port 27' by way of the interior of the casing 22''. These ports are closed or opened according to the position of a disk valve 24' which constitutes an armature for an electro-magnet 23'.

Under normal conditions, the pressure in the chamber 13' passing through the ports 26', forces the armature valve 24' against the port 25' and covers it so as to exclude atmospheric pressure. The pressure in chamber 13' has access to bellows 18' so that the expansion thereof keeps the valve 21' against the port 16', excluding atmospheric pressure through said port. Consequently, the pressure in chamber 13' has access to bellows 19' and expands the latter forcing up the stem 20'. If, however, the magnet 23' is energized through its circuit 70, 71, supplied by battery U, the armature 24' is attracted to the poles of the magnet, thereby covering and closing the port 26', shutting off communication between chamber 13' and bellows 18' and admitting atmospheric pressure into port 27'. The pressure in chamber 13' be-

ing greater than the atmospheric pressure, immediately forces up the lower member of bellows 18' and causes the valve 22' to close the opening 14'. Pressure to bellows 19' being cut off, the pressure therein escapes through the port 16' and the pressure in chamber 13' collapses said bellows so that the stem 20' is moved and the lever 29' which is attached to the switch bar 30' corresponding to the organ controlled by the apparatus L selected, causes all of the sixty-one contacts 31' of said bar 30' to engage with all the metallic plates N' as indicated at 32' which control the given organ. The four apparatuses L, respectively control the playing of the organs 100, 101, 102, 103, and are in turn operated only when the perforation in the music sheet registers with a selected opening in any of the series T'. Unless the set of contacts 31' engages the set of plates N' which control the circuits S^{10} , S^{11} , S^{12} , S^{13} , for the given organ, that organ cannot be played.

In order, however, that when this contact on the switch-board is established it may continue, an apparatus such as shown in Fig. 5 is provided. The circuit 70 is provided with a switch 33' which is controlled by a handle or lever 51' pivoted at 49' and provided with a cam part adapted to operate the contacts 33', there being provided a bar or projection 48' attached to the lever 51' and operated by a rod 47', which in turn, is shifted in one direction or the other by bellows 46' and 50'. The bellows 46' is used to close the circuit at 33' and the bellows 50' to open said circuit. The entire apparatus is designated O'. This apparatus is controlled by the controlling apparatus O. If no music sheet is used and the instrument played manually, the organist may operate the handles 51' at will to control the organs 100, 101, 102, 103.

The controlling apparatus O, Figs. 1, 3 and 5, has a suction chamber 34' which receives suction from the suction reservoir. In this apparatus is a chamber 44' which has a pipe 45' leading to bellows 46', and the apparatus O being duplex, there is another chamber 44'' in communication with bellows 50' by a pipe 45''. According as suction is admitted to chamber 44' or 44'' from suction chamber 34', one or the other of the bellows 46' or 50' will collapse. At 38' is shown a bellows carrying a stem 39' to which is attached a valve 40' which is adapted to seat against either the ports 41' or 42', the latter leading to the atmosphere. In the lower part of the apparatus is an electro-magnet 43' which is in the circuit 71. This electro-magnet controls an armature valve 35' mounted on a spring 36' which tends to keep it normally closed against a port 37'. Normally the atmosphere passes through opening 37' into the bellows 38' and the suction

in chamber 34' draws up the bellows and causes the valve to close the atmospheric port 42' and the suction passing through port 41' and chamber 44' and through pipe 45' into bellows 46', causes the latter bellows to collapse and carry up with it its lower arm and stem 47', thereby closing the circuit at 33'. The lever 51' is provided so that the switch can be closed by hand, if desired, as for instance when the organ is played by hand without using a music sheet for the tracker bar, and it is desired to control the organ stops manually. The collapse of the bellows 46' maintains the circuit at 33'. The mechanism O is duplex and is adapted to operate the bellows 50' just as the bellows 46' is operated, when it is desired to break the circuit at 33'. When the breaking of the circuit at 33' is desired, the collapse of the bellows 50' accomplishes that action.

Referring now to Fig. 6, which shows the mechanism for operating the organ pipes, in connection with Fig. 1, the pipes P of the respective organs 100, 101, 102, 103, are arranged in rows, the rows being under the control of a sliding valve P¹⁰ which has holes registering with the openings leading to the various organ pipes P on that line so that by shifting the valve P¹⁰, the holes may be opened or closed. The valves P¹⁰ are operated at both ends by electro-pneumatic mechanisms like the mechanism L, Fig. 2, and they have stems or arms 20' connected to the valves P¹⁰ and adapted to pull them out or to reverse them so as to play the given combination of pipes P or not. The circuits for the organ stop operated actions which are designated L⁵⁷ and L⁵⁸, are shown at Q, being controlled by certain of the pneumatic switches K⁴.

The mechanism M, Figs. 1 and 6, operates in a manner somewhat similar to the operation of the apparatus L.

The apparatus M has a pressure chest 13^a connected to the pressure reservoir, a valve 56^a controlling admission of pressure to the pipe P, a valve operating bellows 19^a subject to pressure from chamber 13^a through ports 14^a and 15^a or to the voiding of its pressure through port 16^a. The ports 14^a and 16^a are controlled by a valve 22^a on a stem 21^a connected to bellows 18^a which receives pressure through a port 27^a and through ports 26^a leading to chamber 13^a. An electro-magnet 23^a controls an armature valve 24^a which either closes the atmospheric port 25^a or is attracted by the magnet 23^a and made to close the ports 26^a. The operation is substantially the same as with the apparatus L.

The rows of holes T², T³ are controlling holes, while the holes 2, 2^a; 3, 3^a; 4, 4^a; 5, 5^a; 6, 6^a of series T' control the switches and there is a coöperation as will presently appear,

The holes along the same horizontal line 2, 2^a; 3, 3^a, etc., including the hole T⁴, lead to the various pneumatic switches K⁴ through the tubes K³ as follows: 2 connects to its pneumatic switch K⁴ which when put in action, closes the circuit through the electro-magnet 43', which thereupon attracts the armature 35' and bellows 38' thereupon rises, causing the valve 40' to close the port 42'. The suction in 34' draws the air through 75 passage 44' and pipe 45' from bellows 46', thereby closing the contacts 33' and the circuit is then completed to the electro-pneumatic apparatus L, and consequently, the electro-magnet 23' attracts the armature 80 valve 24', which results in collapse of bellows 19' and the drawing down of the lever 29' by the stem 20', thereby making contact through switch bar 30' and its contacts 31' with plates N' as well as all the other plates 85 across the switch-board at that point to the number of sixty-one for the given organ, in this instance solo organ 103. The operation for each organ is the same.

A perforation in the music sheet passes 90 along the tracker-board T and comes into register with the left-hand opening of the playing holes 1' which, let us say, is to play the "C" note. The atmosphere passing through the pipe leading from that particular playing hole to its corresponding pneumatic-electric switch K, will cause electrical contact to be made at 52' and the electric current will pass into the proper conductor of cable 53' leading to one of the contacts 95 31', thence through to the corresponding electro-pneumatic apparatus M in the solo organ chest, whereupon the apparatus M, causes the pipe P to speak if the valve P¹⁰ has been properly set. The stop-setting or controlling apparatus L⁵⁷, L⁵⁸, is controlled in a similar manner by other holes among the controlling holes, as for instance by the holes, 7, 7'.

However, as long as the master hole Z remains closed, no operations will take place, regardless of how many perforations pass over the different holes in the tracker T, for the reason that while the electric circuit will be otherwise completed from the battery 110 through the various circuit connections controlled by the note holes (if any are uncovered), the circuits are not completed past the switch-board N unless the switch is thrown in at the switch-board. The switches 115 are thrown in by the uncovering of the controlling holes T'. For instance, assuming that a hole in the music sheet coincides with the master hole Z, at the same time a hole in the music sheet registers with the hole 2 of 120 right-hand series of holes T', the magnet 43' will be energized and close the switch 33', setting the apparatus L in motion and closing the switch bar of the solo switch 30'. Conditions are then such that any note in the 125 130

solo organ may be played as soon as a hole 1' in the tracker-board T registers with a hole in the music sheet.

I have set forth the action of only one set of the controlling holes of the tracker-board. The action of all other holes is similar. The holes 2 and 2^a, 3 and 3^a, 4 and 4^a, 5 and 5^a of the controlling holes T', control the throwing off and on of the switches at the electric switch-board. Only four switches are shown, but if it is desired to have more organ actions, a greater number of switches are used and additional holes are provided in the tracker to control them, and in that connection, it is to be understood that it is immaterial which of the holes in the perpendicular lines outside of the master hole Z and controlling holes T², etc., are used for this purpose, excepting that the hole used to throw the switch on and that used to throw the same switch off must not be in the same line.

In addition to the holes 2, 2^a; 3, 3^a, etc., there are other holes in the series T' which are numbered from 1 to 100, more or less, which may be used for controlling devices of any character such as pulling additional stops off and on, manipulating additional switches, etc., if desired.

With this system of control, the number of holes necessary for the different operations is greatly reduced; for instance, if it is desired to operate the control represented at 2 and also a stop which is controlled by the opening 9 of the tracker, the holes in the music sheet will be so timed that one opening will register with 2, another opening with 9, another opening with T⁴, another opening with T⁵ and another opening with the master hole Z. It will be seen that although the hole which is to register with T⁵ passes directly over the hole T⁴, no result occurs until it reaches its proper destination for the reason that there is no electrification of any of those horizontal lines controlled by those holes until an opening registers with the master hole Z, whereupon the entire line of controlling holes T⁴, T⁵, etc., is electrified perpendicularly and then each of the lines horizontally which have been registered with holes in the music sheet such as T⁴, 2, 2^a, 3, 3^a, 4, 4^a, and T⁵, 7, 7^a, 8, 8^a, 9, 9^a, etc., are also electrified and are ready to act.

I wish it understood that the controlling holes T', T² do not in and of themselves operate the mechanisms in the wind chest which produce the music, but they merely control the switches on the electric switch-board so as to put the system in condition to receive the electrical current when the proper opening in the music sheet registers with one of the playing holes 1' and the electricity is then conveyed to the proper motor M, or perhaps to four motors in as many separate wind chests, if all four switches are on so

that all four in that case will speak, although only one hole of the speaking holes has been uncovered. Consequently, one opening of the series 1' is made to play a note in all of the separate organs 100, 101, 102, 103, or one or more of those organs may be selected as desired.

The openings 1' are all pipe sounding openings except those indicated 1'' which are included in the series T', and T² in series T². The holes T' are only used for controlling stops or swell shutters. Any of the holes of series T' can be used such as a few of a few series, or an entire set in all of said series but no holes of series T' produce any effect, when uncovered by the music sheet, unless an opening in the music sheet also registers at the same time with master hole Z and another music sheet perforation simultaneously registers with one of the holes T⁴, T⁵, etc. in the same horizontal line with the hole or holes of any of the series T' which are opened.

The switch K and its circuit 60' are controlled and energized as with the other switch K and the circuit 53'.

Having thus described my invention, what I claim as new and desire to secure by Letters Patent, is:

1. In a self-playing musical instrument, the combination with a tracker-board having a row of note openings and, in addition thereto, controlling openings and a master opening, all located to be covered and uncovered by a music sheet, of means for controlling the playing of the musical instrument by the joint control of the master opening and controlling openings through simultaneous uncovering thereof.

2. In a self-playing multi-action musical instrument, the combination with a tracker-board having note openings, a plurality of controlling openings, and a master opening, all located to be covered and uncovered by a music sheet, of a plurality of actions, and means under the joint control of the controlling openings and the master opening through simultaneous uncovering thereof whereby any musical action may be played alone or a plurality of them played simultaneously by the note openings.

3. In an electro-pneumatically controlled self-playing musical instrument, the combination with stops or sound-controllers therefor, of electro-pneumatically operated means for controlling said stops, electro-pneumatically controlled switches which control the circuits of said electro-pneumatically operated means aforesaid, a trackerboard having note openings and also controlling holes whereby the switches are automatically operated, and manually operable means for throwing said switches independently of their automatic operation, whereby the stops may be automatically operated from the

tracker-board or manually operated, said controlling holes and note openings being located for covering and uncovering by the same music sheet.

5. 4. In an electro-pneumatic organ, the combination with a trackerboard having note holes and a master hole which must be opened by the music sheet to permit any note to be sounded, of electro-pneumatic means controlled by the note holes adapted for sounding the organ pipes, and electro-pneumatic means controlled by the master hole which in turn controls the operation of the electro-pneumatic means first-named, the note holes and master hole being located to be covered and uncovered by the same music sheet and to jointly and selectively cause the sounding of the notes by the simultaneous uncovering of the master hole and note holes.
10. 5. In an electro-pneumatically controlled self-playing musical instrument, the combination with a trackerboard having note openings, a plurality of controlling openings and a master opening, all located to be covered and uncovered by a music sheet, of electrically operated means for controlling the operation of the said musical instrument, electro-pneumatic means for controlling the supply of current to said electrically operated means, and means under the joint control of the master opening and controlling openings through simultaneous uncovering thereof for supplying current to said electro-pneumatic means.
15. 6. In an electro-pneumatically controlled musical instrument, the combination with stops or sound-controllers therefor, of electro-pneumatically operated means for controlling said stops, and combined manually and pneumatically operated electric switches subject to either automatic or manual operation at will which control the circuits of said electro-pneumatically operated means aforesaid.
20. 7. In an electro-pneumatic organ, the combination with a trackerboard having note holes, a plurality of controlling holes, and a master hole, of electro-pneumatic means controlled by the note holes adapted for sounding the organ pipes, electro-pneumatic means controlled by the controlling holes adapted for controlling the organ actions, and electro-pneumatic means controlled by the master hole which in turn controls the operation of the electro-pneumatic means first and second named, the note holes, controlling holes, and master hole being located to be covered and uncovered by the same music sheet, whereby the notes can only be sounded when the master hole, controlling holes and note holes are simultaneously uncovered.
25. 8. In an electro-pneumatically controlled self-playing musical instrument, the combination with a trackerboard having note holes, a plurality of controlling holes, and a master hole, of electro-pneumatic means controlled by the note holes adapted for sounding the organ pipes, electro-pneumatic means controlled by the controlling holes adapted for controlling the organ actions, and electro-pneumatic means controlled by the master hole which in turn controls the operation of the electro-pneumatic means first and second named, the note holes, controlling holes, and master hole being located to be covered and uncovered by the same music sheet, whereby the notes can only be sounded when the master hole, controlling holes and note holes are simultaneously uncovered.

bination with a trackerboard having note openings, a plurality of controlling openings, and a master opening, said note openings, controlling openings and master opening being located to be covered and uncovered by the same music sheet, of electro-pneumatic means for controlling the playing of the musical instrument, independent pneumato-electric switches in communication with the controlling openings aforesaid, a pneumato-electric master-switch in communication with the master opening aforesaid, electric circuits for operating the electro-pneumatic musical instrument controlling means aforesaid under the control of the independent pneumato-electric switches, said master switch controlling the aforesaid circuits of said pneumato-electric switches, and said master opening and controlling opening being adapted by covering and uncovering by the music sheet to exercise a joint control over the electrical circuit aforesaid.

30. 9. In an electro-pneumatically controlled self-playing musical instrument, the combination with a trackerboard having note openings, a plurality of controlling openings, and a master opening, said note openings, controlling openings and master opening being located to be covered and uncovered by the same music sheet, of a plurality of actions, electrically operated means for controlling the operation of one or any number of said actions, and pneumato-electric devices under the joint control of the controlling openings and master opening by covering and uncovering by the music sheet which openings control the energization of the electrical controlling means.

35. 10. In an electro-pneumatically controlled self-playing musical instrument, the combination with a trackerboard having note openings, a plurality of controlling openings, and a master opening, said note openings, controlling openings and master opening being located to be covered and uncovered by the same music sheet, of a plurality of actions, electrically operated means for controlling the operation of one or any number of said actions, an electric switch-board for controlling the supply of current to the electrically operated means aforesaid, electro-pneumatic means adapted for operating said switch-board, and pneumato-electric means under the control of the master opening and controlling openings by covering and uncovering by the music sheet adapted for supplying current to the switch-board and for controlling the switch-board operating means aforesaid, whereby one or more of the musical actions can be selectively controlled.

40. 11. In an electro-pneumatically controlled self-playing musical instrument, the combination with a trackerboard having note openings, a plurality of controlling openings, and a master opening, said note openings, controlling openings and master opening being located to be covered and uncovered by the same music sheet, of a plurality of actions, electrically operated means for controlling the operation of one or any number of said actions, an electric switch-board for controlling the supply of current to the electrically operated means aforesaid, electro-pneumatic means adapted for operating said switch-board, and pneumato-electric means under the control of the master opening and controlling openings by covering and uncovering by the music sheet adapted for supplying current to the switch-board and for controlling the switch-board operating means aforesaid, whereby one or more of the musical actions can be selectively controlled.

openings, a plurality of controlling openings and a master opening, said note openings, controlling openings and master opening being located to be covered and uncovered by the same music sheet, of electrically operated means for controlling the operation of said musical instrument, an electric switch-board for controlling the supply of current to said electrically operated means, electro-pneumatic means adapted for operating said switch-board, and pneumato-electric means under the control of the master opening and controlling openings by covering and uncovering by the music sheet adapted for supplying current to the switch-board and for controlling the switch-board operating means aforesaid.

12. In an electro-pneumatically controlled self-playing musical instrument having stops or sound controllers, the combination with a trackerboard having note openings, a plurality of controlling openings and a master opening, said note openings, controlling openings and master opening being located to be covered and uncovered by the same music sheet, of electrically controlled devices for operating said stops, pneumato-electric devices communicating with the controlling openings and with the master opening aforesaid and in turn controlled thereby, electric circuit connections controlled by and interposed between said pneumato-electric devices and said stop-controlling devices, electrically controlled means for operating said musical instrument, an electric switch-board for controlling said musical instrument operating means, electro-pneumatic means for operating the switchboard, pneumato-electric means adapted, under the control of the tracker-board, for controlling the operation of the switchboard operating means, and electric circuit connections for supplying current to the switch-board.

13. In an electro-pneumatically controlled self-playing musical instrument having stops or sound controllers, the combination with a trackerboard having note openings, a plurality of controlling openings and a master opening, said note openings, controlling openings and master opening being located to be covered and uncovered by the

same music sheet, of electrically controlled devices for operating said stops, pneumato-electric devices communicating with the controlling openings and with the master opening aforesaid and in turn controlled thereby, electric circuit connections controlled by and interposed between said pneumato-electric devices and said stop-controlling devices, electrically controlled means for operating said musical instrument, an electric switch-board for controlling said musical instrument operating means, electro-pneumatic means for operating the switchboard, pneumato-electric means adapted, under the control of the tracker-board, for controlling the operation of the switchboard operating means, and electric circuit connections for supplying current to the switch-board.

14. An electro-pneumatic apparatus having a chamber, an operating pneumatic contained within the chamber and adapted to be placed in communication therewith or with the atmosphere, a valve controlling such communication, a controlling pneumatic for operating the valve, electrically operated means for controlling the communication of the controlling pneumatic with the chamber first-named and also for controlling its communication with the atmosphere, an electric switch-board, means operated by the pneumatic first-named adapted for controlling the contacts of the switch-board, an electrically controlled musical instrument whose electrical connections are controlled by said switch-board, a tracker-board, and pneumato-electric means controlled by the tracker-board for controlling the supply of electrical current to the switch-board.
